US00D749744S

(12) **United States Design Patent**
Drey et al.

(10) **Patent No.:** US D749,744 S
(45) **Date of Patent:** ** Feb. 16, 2016

(54) **HEEL PROTECTOR**

(71) Applicant: **Medline Industries, Inc.**, Mundelein, IL (US)

(72) Inventors: **Michelle Drey**, Chicago, IL (US); **Margaret Falconio-West**, Round Lake, IL (US); **Bruce Shapiro**, Deerfield, IL (US)

(73) Assignee: **Medline Industries, Inc.**, Mundelein, IL (US)

(**) Term: **14 Years**

(21) Appl. No.: **29/473,963**

(22) Filed: **Nov. 27, 2013**

Related U.S. Application Data

(63) Continuation of application No. 29/444,693, filed on Feb. 1, 2013, now Pat. No. Des. 697,628.

CLAIM

The ornamental design for a heel protector, as shown and described.

DESCRIPTION

FIG. 1 is an isometric view of a heel protector showing our new design;

FIG. 2 is a side elevation view thereof;

FIG. 3 is a side elevation view thereof;

FIG. 4 is a top plan view thereof;

FIG. 5 is a bottom plan view thereof;

FIG. 6 is a rear elevation view thereof;

FIG. 7 is a front elevation view thereof;

FIG. 8 is an isometric view of the heel protector in a second state;

FIG. 9 is a side elevation view thereof;

FIG. 10 is a side elevation view thereof;

FIG. 11 is a top plan view thereof;

FIG. 12 is a bottom plan view thereof;

FIG. 13 is a rear elevation view thereof;

FIG. 14 is a front elevation view thereof;

FIG. 15 is an isometric view of a heel protector showing our new design;

FIG. 16 is a side elevation view thereof;

FIG. 17 is a side elevation view thereof;

FIG. 18 is a top plan view thereof;

FIG. 19 is a bottom plan view thereof;

FIG. 20 is a rear elevation view thereof;

FIG. 21 is a front elevation view thereof;

FIG. 22 is an isometric view of the heel protector in a second state;

FIG. 23 is a side elevation view thereof;

FIG. 24 is a side elevation view thereof;

FIG. 25 is a top plan view thereof;

FIG. 26 is a bottom plan view thereof;

FIG. 27 is a rear elevation view thereof;

FIG. 28 is a front elevation view thereof;

FIG. 29 is an isometric view of a heel protector showing our new design;

FIG. 30 is a side elevation view thereof;

FIG. 31 is a side elevation view thereof;

FIG. 32 is a top plan view thereof;

FIG. 33 is a bottom plan view thereof;
FIG. 34 is a rear elevation view thereof;
FIG. 35 is a front elevation view thereof;
FIG. 36 is an isometric view of the heel protector in a second
state;
FIG. 37 is a side elevation view thereof;
FIG. 38 is a side elevation view thereof;

FIG. 39 is a top plan view thereof;
FIG. 40 is a bottom plan view thereof;
FIG. 41 is a rear elevation view thereof; and,
FIG. 42 is a front elevation view thereof.
